DESIGN FOR A MOTOR VEHICLE

Levina W. Harris, Portland, Oreg.

Application September 14, 1943, Serial No. 111,123

Term of patent 7 years

(Cl. D14—3)

To all whom it may concern:

Be it known that I, Levina W. Harris, a citizen of the United States, residing at Portland, in the county of Multnomah and State of Oregon, have invented a new, original, and ornamental Design for a Motor Vehicle, of which the following is a specification, reference being had to the accompanying drawings, forming part thereof.

I claim:

The ornamental design for a motor vehicle, as shown.

LEVINA W. HARRIS.
